UNITED STATES PATENT OFFICE.

FREDERICK W. KENNEDY, OF SHELBYVILLE, INDIANA, ASSIGNOR TO THE KENNEDY CAR LINER & BAG CO., A CORPORATION OF INDIANA.

GARMENT BAG.

Application filed December 12, 1921. Serial No. 521,793.

To all whom it may concern:

Be it known that I, FREDERICK W. KENNEDY, citizen of the United States, residing at Shelbyville, in the county of Shelby and 5 State of Indiana, have invented certain new and useful Improvements in Garment Bags; and I do hereby declare the following to be a full, clear, and exact description of the invention, such as will enable others skilled 10 in the art to which it appertains to make and use the same.

This invention relates to new and useful improvements in garment bags, the main object of the present invention being the 15 provision of a garment bag for the purpose of protecting clothing or garments against dirt, moths and the like and whereby access is gained to the receptacle through one of the side walls thereof and having suitable 20 means of suspension connected to the top portion of the bag.

A further object of the present invention is the provision of a garment bag having an opening at one side which is folded and the 25 folds secured so as to provide a dirt proof and air proof garment receptacle whereby to exclude all fine particles of dust and other objects from the interior of the receptacle.

With the above and other objects in view, 30 the invention consists in the novel features of construction, combination and arrangement of parts hereinafter more fully set forth, pointed out in the claims and shown in the accompanying drawings, in which:

35 Figure 1 is a front elevation of a garment receptacle constructed in accordance with my invention, a portion of the closure being unfolded to disclose the manner in which the side edges are folded together;

40 Fig. 2 is a transverse sectional view taken on the line 2—2 of Fig. 1;

Fig. 3 is a transverse sectional view taken on the line 3—3 of Fig. 1, and

45 Fig. 4 is a detail vertical sectional view illustrating the manner of securing the hanger to the receptacle.

In carrying out the invention, the bag is formed of a single piece of material, folded substantially intermediate its side portions 50 to form the side walls 1 and 2, while one end of one of the side walls is folded upon the other as shown at 3 to close one end of the bag. The other end of the bag is closed by having one of the side walls provided with flaps 4 overlapping the opposing side

wall and secured thereto by pasting or in any other suitable manner.

Suitable means for suspending the receptacle is provided in the shape of a hook 5 having a shank 6 extending through a suitable opening in the top of the receptacle and provided at its inner end with a loop 7. The shank of the hook is retained in its proper position by engaging over the upper edge of the bag a U-shaped clip 8 provided 60 with transverse perforations extending through the side walls thereof and further provided with a perforation 9 intermediate its ends through which the shank 6 of the hook projects. A staple member 10 extends 70 through one side of the clip 8, the prongs of said staple projecting upon opposite sides of the shank 6 as they pass through the opening in the clip 8 upon the opposite side, said prongs being bent outwardly upon one 75 face of the clip 8 to thus securely fasten the clip 8 to the shank 6 of the hook and prevent any withdrawal of the loop 7 which is disposed upon the interior of the bag.

In order to prevent the movement of the 80 loop 8 from wearing through the material of which the bag is constructed, suitable reinforcing pads 11 are attached to the interior of the bag and arranged so as to receive any contact from the loop 7 which might otherwise be conveyed to the material from which the receptacle is constructed and prevent any 85 wearing on the body of the receptacle.

In order to close the receptacle and provide a dust proof and air tight closure, the 90 side wall 2 of the receptacle has its longitudinal edge projecting beyond the edge of the wall 1 and is folded upon itself as shown at 12 to form a reinforced part for a socket member 13 of the snap or glove fastener. 95 The portion 12 is then disposed against the longitudinal edge 1^a of the side wall 1 and both members are then folded inwardly upon themselves so that the socket member 13 will engage with the stud 14 which is secured 100 within the wall 1 adjacent the outer edge thereof. These studs and sockets may be placed at intervals throughout the length of the bag so as to securely retain the folded portions in their closed positions. A suitable reinforcing strip 15 is secured to the interior of the wall 1 so as to prevent the studs, which are pressed into position, from 105 being easily torn from their positions.

In Fig. 3 I have illustrated in detail the 110

side edges of the receptacle in their folded position and it will be readily noted from this manner of folding the side edges, that it provides a substantially air tight fold to thus exclude all dust, dirt and other objectionable objects from the interior of the bag. It will also be apparent from the description taken in connection with the accompanying drawings, that this bag can be manufactured and placed upon the market at a comparatively small cost, as it is extremely simple in construction and the material from which it can be made can be secured at a minimum cost.

15 I claim:

1. The combination with a bag, of means for supporting the bag comprising a hook the shank whereof passes through the top of the bag, a loop at the end of the shank within 20 the bag, reinforcements on the walls of the bag opposite the loop, and means passing

through said reinforcements and straddling the shank to prevent lateral displacement.

2. The combination with a bag, of means for supporting the bag comprising a hook 25 the shank whereof passes through the top of the bag, a U-shaped member clipped over the top of the bag and through which the shank passes, and a staple passing through the clip and straddling the shank.

3. The combination of a bag formed of a single piece of material having its bottom, top and one side closed, closing means for closing the other side, means for supporting the bag comprising a hook, the shank where- 35 of passes through the top of the bag, a U-shaped member clipped over the top of the bag and through which the shank passes, and a staple passing through the clip and stradding the shank.

In testimony whereof I affix my signature.

FREDERICK W. KENNEDY.
